UNITED STATES PATENT OFFICE

ADOLPHUS M. WEBB, OF CHARLOTTE, NORTH CAROLINA, ASSIGNEE OF ONE-FOURTH
TO W. G. JARRELL MACHINE COMPANY, OF CHARLOTTE, NORTH CAROLINA

EXERCISING DEVICE

Application filed April 23, 1928. Serial No. 272,129.

This invention relates to exercising devices and more especially to a device for imparting vibrations to the body of the patient while the patient is in prone position. One of the advantages of my invention is that by the use thereof, health conditions of the body may be improved.

An object of my invention is to provide a massaging or vibrating machine which is so constructed that the entire body of the person will receive a vibratory action, which vibratory action can be regulated to suit the needs of the patient.

Another object of my invention is to provide a massaging machine having an air cushion resiliently mounted on the machine in a suitable framework with vibratory means for imparting vibrations to the human body, together with means for regulating and controlling said vibrations.

Another object of my invention is to provide efficient vibrating means for imparting vibrations to the body to cause a relaxation of the muscles and to stimulate the circulation of the blood thru the system and I have found that by the use of my device poisonous matter is eliminated from the system and the general condition of the human system is improved and the condition of health improved.

Some of the objects of my invention having been stated, other objects will appear as the description proceeds, when taken in connection with the accompanying drawings, in which—

Figure 1 is a side elevation of my device;

Figure 2 is a plan view of the same;

Figure 3 is a cross-sectional view taken along the line 3—3 in Figure 1;

Figure 4 is an enlarged detail view of the resilient supporting means;

Figure 5 is an enlarged detail view, partly in cross-section of my vibrating means;

Figure 6 is an end view of Figure 5.

Referring more particularly to the drawings, the numeral 10 indicates the main frame portion of my device which has the lower horizontally disposed members 11 and the upper horizontally disposed members 12, and the upright portions 13. This framework has the projections 14 and 15 at each corner there-

of in which the extensions 16 and 17 are adapted to rest one of their ends, the other ends of these extensions being supported by the standards 18 and 19 respectively. These extensions are padded as at 20 and 21, the extension 16 being adapted to serve as a rest for the head of the patient and the extension 17 being adapted to serve as a rest for the legs of the patient.

My body supporting element is designated broadly by the numeral 25 and comprises the rectangular framework composed of the side members 26 and the end members 27, and secured at each corner of this frame 25 are the bolts 28 which project downwardly through the corner portions of the frame 10 and have the compression spring 29 loosely secured therearound with the nut 30 threadably engaging the lower end of the bolt 28. This frame portion 25 has the screen 31 secured to the end and side members, which screen is adapted to support the pneumatic mattress 32 and a covering 33 is adapted to be secured over the pneumatic mattress 32 by snap fastener 34, and this pneumatic mattress has the tube 38 by means of which the same may be inflated. In Figure 1 I have shown the covering element 33 unsnapped to show the manner in which the pneumatic element may be inflated, it being apparent that after inflation the cover 33 can be snapped into position.

Secured to the side members 26 are the outwardly and upwardly projecting members 35 which are adapted to have secured therein the handle members 36.

On the longitudinally disposed members 11 I mount the motor 40 which has the pulley 41 thereon, and to the members 42 and 43 which are secured to the lower side of the frame 25 I secure the bearing member 44 which has the ball bearings 45 and 46 therein supporting the shaft 47 on which is mounted the pulley 48 and the unbalanced weights 49 and 50. These cams may be adjusted in any desired position by means of the set screws 51 and 52. This bearing member 44 has the recess 53 in which grease or oil may be deposited for proper lubrication of the bearings 45 and 46. The pulleys 48 and 41 are adapted to have secured thereon the belt 54.

The reinforcing members 55 and 56 are adapted to be secured to the side members 26 to reinforce the same and to prevent the body from coming in contact with these sharp metallic members 26.

It is evident that when the patient takes hold of the handle members 36 that direct vibrations are communicated to the body, as these handle members are connected directly to the frame 25 on which the vibrating means are mounted. This gives a stronger type of vibration to the arms of the patient, which is desirable, as the arms can stand a stronger vibration than the body, and the air cushion causes the body to receive the lighter vibrations.

In operation, the supports 16 and 17 are secured as shown in the drawings and the bag 32 is inflated to the proper degree and the cover 33 is secured in position and the patient is supported on the central part of the machine with the patient's head resting on the support 16 and the patient's feet resting on the support 17. The variable speed motor 40 is then started and due to the unbalanced weights 49 and 50 being properly adjusted on the shaft 47 vibrations are imparted to the framework 25 and to the body of the patient.

My object in providing the pneumatic mattress is to provide means for regulating the intensity of the vibrations received by the patient, as it is evident that if a patient weighing 140 pounds were placed on the device with the pneumatic mattress inflated to five pounds pressure that the intensity of the vibrations would be greater than if the mattress element were inflated to only three pounds pressure. It is also evident that where the patient is light in weight that the normal inflation would be greater to begin with than where the patient is heavier. It is also evident that by providing this pneumatic mattress element that I have provided a device where each portion of the body will receive the vibrations, as the mattress will conform to the curvature of the body of the patient and give vibrations of the same intensity to the portions of the body in engagement with the mattress element.

In the drawings and specification I have set forth a preferred embodiment of my invention, and although specific terms are employed, they are used in a generic and descriptive sense only and not for purposes of limitation, the scope of the invention being set forth in the appended claims.

I claim:

1. An exercising device comprising a framework having resiliently supported thereon a superstructure, a resilient body supporting member carried by the superstructure, a cover for said resilient member, means for fastening the cover to the superstructure, head and foot extensions adapted to be remov-

ably secured to the framework, means on the lower side of the superstructure for imparting vibratory motion to the superstructure, and means on the framework for operating said vibrating means.

2. In an exercising device for the human body, a main frame, a second frame resiliently mounted on the main frame, a mattress supporting element in the second frame, a pneumatic mattress mounted on the mattress supporting means, a removable cover for the mattress, said mattress cover being adapted to be detachably secured to the second frame, means for permitting inflation of the pneumatic mattress, and handle bars disposed on each side of the second frame.

3. In a machine for imparting vibrations to the human body, a main frame having mounted thereon a motor, a superstructure resiliently mounted on the main frame and having supported thereon a pneumatic mattress which is adapted to support the body of the patient, a removable covering for the mattress, means for securing the covering to the sides and ends of the superstructure, and head and foot extensions for supporting the head and feet of the patient, detachably secured to the main frame.

4. In a machine for imparting vibrations to the human body, a main frame, a superstructure resiliently mounted on the main frame, a pneumatic mattress member mounted on the superstructure, means for regulating the degree of resiliency of the mattress member, handle members secured to the superstructure, said handle members being adapted to be held by the patient to receive direct vibrations from the superstructure, and means for imparting vibrations to the superstructure.

5. In an exercising device, a framework, a superstructure resiliently mounted on top of said framework, a transversely mounted shaft on said superstructure, extensions on said shaft, a motor on the framework, driving connections between said motor and said shaft, a pneumatic mattress mounted on said superstructure, a covering adapted to be secured to the sides and ends of said superstructure and to cover said pneumatic mattress, longitudinally disposed handle bars rigidly secured to said superstructure at the sides thereof, removable extension members adapted to be secured to both ends of the framework and being adapted to support the head and foot portions of the human body, the central portion of the human body being adapted to receive indirect vibration through the pneumatic mattress and the human body being also adapted to receive direct vibration when the hands of the human body come in contact with said longitudinally disposed handle bars.

6. In an exercising and vibrating device, a main frame, a framework resiliently mounted on said main frame, a pneumatic mattress ele-

ment mounted on said framework, handle bars mounted along side of said framework, a detachable cover adapted to be secured to said framework and to cover the said pneumatic mattress, an eccentrically mounted shaft on the lower side of said framework, means associated with the main frame adapted to impart rotation to the said shaft and to create vibration to said framework and head and foot sections adapted to be removably secured to the head and foot portions of the main frame.

In testimony whereof I affix my signature.
ADOLPHUS M. WEBB.
